UNITED STATES PATENT OFFICE.

GEORGE S. KNAPP, OF LA GRANGE, ILLINOIS.

METAL BASE-BOARD.

1,143,283.

Specification of Letters Patent. Patented June 15, 1915.

Application filed February 19, 1914. Serial No. 819,718.

To all whom it may concern:

Be it known that I, GEORGE S. KNAPP, a citizen of the United States, residing at La Grange, in the county of Cook and State of Illinois, have invented certain new and useful Improvements in Metal Base-Boards, of which the following is a specification.

My invention relates to improvements in metal base boards and fittings for vertical walls of rooms as usually employed in fire-proof buildings.

One of the objects of my invention is to provide a metal base board, that is cheap to construct; readily held in place by the plaster and floor structures, independently of its temporary holding means, and which serves to unite and hold the plaster, and plastic material of the composition floor in intimate contact therewith.

Another object of my invention is to provide means for joining the ends of longitudinal sections of the board, by plates, arranged to neatly fit the board so as to back up, or reinforce the sheet metal portions to prevent any inward deflection thereof at the joints; the relative displacement of which would render visible the otherwise substantially invisible joint. The board being perforated at the shoulders, provided at its longitudinal edges, plaster will pass down through such upper perforations and mastic floor composition will pass up through the perforations provided in the lower edge and thus back up the intermediate major portion of the board and thereby the entire board is reinforced from end to end.

Still another object of my invention is to provide means to temporarily hold the board parts to the wall until the more substantial holding means, such as the plastic material of which the wall and floor may consist is substantially applied thereto.

Other and further objects of my invention will become readily apparent to persons skilled in the art from a consideration of the specification when taken in conjunction with the drawings, wherein—

Figure 1 is an elevation of a portion, or fragment, of the structure as it would appear when applied to the wall showing means of making a joint between the abutting ends of contiguous sections. Fig. 2 is a section taken on line 2—2 of Fig. 3. Fig. 3 is an elevation showing two abutting ends of adjoining sections. Fig. 4 is a section of a modification showing the lower portion of

the base board of a form preferably used when a plastic floor is to be constructed in association with my metal base board. Fig. 5 is an elevation, part of which is broken away and shown in section, of the base board and the means of turning angles and corners. Fig. 6 is a fragmentary section, taken on line 6—6 of Fig. 5.

In all the views the same reference characters are employed to indicate similar parts.

My base board is of that character of trim that is applied to the lower margin of the vertical walls of rooms and immediately above the floor, as usual in such room structures. Base boards, of this general type, especially wooden base boards, are usually applied after the plastering has been completed to the floor line and the floor has been laid. My board, however, is placed in position and held, by temporary attaching means, to the rough vertical walls of a room, before the plastering has been completed, and before the final finished floor has been laid, and when so placed its upper forwardly projecting edge of the body part, serves as a ground to which to finish the plastering.

In fire proof buildings, where metal base boards are to be used, it is very desirable that such boards, when completed and finished, shall simulate the appearance of wood, and therefore it is very desirable to have the temporary attaching means subsequently covered by later applied finish, such as the plaster applied to the vertical walls and the floor, and hidden from the view of the observer.

In the drawings 10 represents the vertical wall, to which the plaster and the base board are to be subsequently applied. It may be composed of brick or may be a wall made of terra cotta, cement, or other suitable fire proof material, as in fire proof structures, or if desired, the wall may be of wood, in so far as the application of my base board thereto is concerned.

The board 11 is made of adjoining strips of sheet metal, preferably in sections of uniform length, adapted to be connected together at abutting edges, by specially designed joining means to be hereinafter more particularly described.

The main, vertical, exposed face portion 12 of the board is adapted to be spaced apart from and parallel with the wall 10, a distance substantially equal to the thickness of the plastering 13, which space is to be sub-

sequently filled with plastic material. The upper edge of the board is deflected rearwardly and downwardly, as at 14, and then vertically as at 15, to provide a more or less acute angular, longitudinal, groove 16, for inclusion of the plaster 13. The upper edge of the board, as at 17, affording a ground or guide to which the plaster is to be finished and providing a longitudinally extending straight edge or border to be flush with the lower margin of the plaster. The strip is again bent downwardly, as at 18, and upwardly, as at 19, the latter portion being the base part which is in a substantially parallel plane with the body portion 12, of the strip and which portion is designed to be placed in contact with and temporarily secured to the supporting wall 10. Between the walls 18 and 19 of the strip is provided another groove 20, within which to contain a portion of the plaster 13 and to provide a blunt terminal edge of the plaster and to more securely hold the plaster and the upper edge of the base board in intimate association.

To still further key the parts together I provide perforations 21-21 at intervals in the wall 15 of the inwardly deflected ledge portion of the upper surface of the board. The plaster, which passes through the perforations, furthermore serves as a support against inward deflection of the board and assists in preventing any relative separation of the parts. The base margin 19 is provided at intervals with slots 22, and smaller perforations 23, within both or either of which to insert the temporary attaching means 24 which may be screws, bolts, or nails. The lower base edge 19', of the structure, is also provided with slots 22 and holes 23, for the reception of the holding means 24. The vertical body part or wall 12, is curved outwardly, as at 25, so as to obviate the square corner at the juncture of the floor 45 and the vertical portion of the base board and so as to provide a projecting bead or nose which will overlie or cover the marginal edge of the floor. At the extreme edge 26, of the curved portion, the wall is deflected rearwardly at substantially right angles to the vertical portion 12, as at 27, to overlie the edge of the floor 28. The wall is again deflected, in a vertical direction, as at 29, to form a ledge separated from the wall 55 10, and this portion of the structure is provided with a series of plaster receiving openings 30 similar to the openings 21 provided in the upper edge of the board to permit plaster to pass through and key in the openings 30 and to fill the space back of the board. At the lower edge of the ledge 29, the wall is again deflected at substantial right angles to the part 27, as at 31, and finally is deflected again at right angles to 60 65 provide the base portion 19, which is de-

signed to rest against the surface of the vertical wall 10.

When the floor 28 is to be made of composition plastic material, such as concrete, or the like, the composition will key through the openings 30-30 just as the plaster 13 keys through the openings 21-21, located at the top of the board, and by this means the lower portion of the board is thus firmly held in place by the composition floor. When a wood floor is used, as shown in Fig. 5, the proximate edges of the wood boards are adapted to abut against the vertical wall 31, which, together with the temporary fastenings, nails or screws 24, serves to hold the lower portions of the structure against longitudinal or transverse movement. To join abutting ends of the continuous board sections 12 I provide a joining plate 32, undercut, as at 33, to save material, and having end base portions 34 and 34' which are to be placed in substantially the same vertical plane as are the base portions 19 and 19' of the structure 11, and which base portions 34-34' rest against the vertical wall 90 upon which the board is to be applied. The front surface 35, of the plate, is substantially of the same configuration as the cross sectional inner surface of the board 11, and fits into the cavity or channel formed in the board 11 by the various transverse deflections of the marginal edges thereof, so that the parts 11 and 25, of the board, are in intimate contact with the plate and thus the plate 32 backs up, or reinforces, these exposed portions of the section, at the joints, so that when an adjacent board section is slipped over the exposed end of the plate 32, the vertical meeting edges of the adjacent board sections will be defined by a very fine 105 line, thus rendering the joints between sections, almost invisible.

Perforations are made in the base portion 20 for insertion of attaching screws 36 which are screwthreaded into perforations 37 provided in the joining plate 32. When these screws are inserted in their respective screw threaded apertures, at the bottom and top of the board, they apply a transverse tension stress to the body part of the board 110 tending to stretch it along the presented surface over the joining plate 32, thereby bringing up the joining ends of adjacent strips snug into a common plane in contact with the plate, thereby preventing unevenness and springing of the sheet metal at the joints, and firmly holding the parts against possibility of subsequent relative displacement. When the plastering and the floor are applied to the structure the screws 36 will be hidden from view, as indicated in Fig. 2. By undercutting the joining plate 32, as at 33, I not only economize in the use of metal, but render it unnecessary to prepare the wall under the entire base portions 115 120 125 130

of the plate in order that the plate may be truly positioned with reference to the wall structure 10 and therefore considerable economy in labor expense is effected in this 5 respect.

In the inner corners of the room I provide a plate 32' similar in every respect in cross section to the plate 32 except that it is curved through an angle of about 90 degrees, depending upon the angle of the corner. This plate is usually made of cast iron and provides substantially the same means of connecting the ends of the adjacent board sections, with the exception that 10 the presented face of the casting 32' is preferably flush with the front faces of the sheet iron sections, on either side, and therefore the casting surface is, in effect, a continuation of the sheet iron section. The salient 15 corners, or angles of the room, substantially as shown near the center of Fig. 5, are taken care of by a plate 32^a, which is curved as shown in Fig. 6, the rounded, presented surface of which, at the corner, is taken 20 care of in the same manner as in the inner corner, the presented surface being flush with the section 11 presenting a continuation 25 of the surface flush with that of the section. The sections 11 are secured to the plate 32^a in the same manner as they are secured to the plate 32, as by screws 36. The presented surface of the plate 32^a, up to the extreme height of the base board, is 30 of the same general configuration as the corner bead structure 38, which registers with and extends from the plate 32^a to the ceiling of the room. This corner bead 38 is the subject matter of my United States Patent No. 1,049,783, dated January 7th, 35 1913, and needs no further description here.

In the modification shown in Fig. 4 I may extend the part 27 deeper in a vertical direction as shown at 27' so that the composition floor, made of plastic material, 28' 40 may extend up to the salient angular edge between parts 25 and 27 of the base board, so as to be in the plane of the curved portion 25 or to be flush therewith at the point where the floor and the base board meet. 45 It is evident that the preferred form of my structure may be employed with a composition floor, but the variation shown in Fig. 4 may, in some instances, be preferable.

It will be observed that there is no fitting 50 or changing of the structure necessary for

its application to the wall and in shipping the material necessary for its composition, I prefer to secure a plate 32 to one end of each of the sections 11 by means of the attaching screws 26, so that it will only be 55 necessary to insert the end of the adjoining section over the plate 32 and insert the proper screws for making the connection between any two adjoining sections.

While I have herein shown a single embodiment of my invention for the purpose of clear disclosure it is evident that changes may be made therein within the scope of the appended claims.

Having described my invention, what I claim is:—

1. A metallic base board adapted for use with a plastered wall, comprising a strip of sheet metal, a vertical face portion formed from said strip and adapted to lie 75 in the plane of the plastered surface, longitudinal attaching portions formed from each longitudinal edge of the strip and lying in a plane parallel, and at the rear of, the plane in which the face portion lies, 80 and intermediate, longitudinal ledges formed from said strip intermediate the face portion and the attaching portions, said ledges having perforations at intervals substantially as and for the purpose set forth. 85

2. A metallic base board adapted for use with a plastered wall, comprising a strip of sheet metal, a vertical face portion formed from said strip and adapted to lie 90 in the plane of the plastered surface, longitudinal attaching portions formed from each longitudinal edge of the strip and lying in a plane parallel with, and at the rear of, the plane in which the face portion lies, and intermediate longitudinal 95 ledges formed from said strip intermediate the face portion and the attaching portions, and having their major parts disposed in a plane parallel with the plane containing the face portion and between the plane of the face portion and that containing the attaching portions, said ledges having perforations substantially as set forth.

In testimony whereof I hereunto set my hand in the presence of two subscribing 105 witnesses.

GEORGE S. KNAPP.

In the presence of—

STANLEY W. COOK,
MARY F. ALLEN.
